UNITED STATES PATENT OFFICE.

WILLIAM F. HUTCHINSON, OF LYNN, MASSACHUSETTS, ASSIGNOR OF ONE-HALF TO WARREN B. HUTCHINSON, OF SAME PLACE.

SHOE-VAMP-BURNISHING MACHINE.

SPECIFICATION forming part of Letters Patent No. 356,839, dated February 1, 1887.

Application filed May 26, 1886. Serial No. 203,278. (No model.)

To all whom it may concern:

Be it known that I, WILLIAM F. HUTCHINSON, a citizen of the United States, residing at Lynn, in the county of Essex and State of Massachusetts, have invented a new and useful Shoe-Vamp-Burnishing Machine, of which the following is a specification.

The object of my invention is to burnish or finish the raw edges of shoe-vamps and uppers where they are exposed to view. I attain this object by the mechanism illustrated in the accompanying drawings, in which—

Figure 1 is a view of the machine with one leg removed so as to show the working parts of the machine; Fig. 2, a view of the burnishing-iron, and Fig. 3 a sectional view of the working parts of the machine.

Similar letters refer to similar parts throughout the several views.

20 A is the frame of the machine.

B is an arm which forms a bearing for the shaft F, and to the lower end of which the link C is attached. The arm B is fastened to the piece a, which is a part of the frame A, and

25 is cast solid with it.

D is a block, which is placed loosely in the square hole in the upper part of the link C. The crank g passes through the block D and is attached to the end of the shaft F.

30 E is the burnishing-iron, which is fastened into a slot in the link C, above the block D, by the screw e. A crease should be cut in the side of the iron E, corresponding in size to the thickness of the leather to be burnished.

35 The iron should be placed in the link C so that the crease in its side will be on nearly the same plane as the top surface of the machine.

H is a circular piece which fits around the iron E, and is held in place by the screw h. It 40 should have a slot in its center large enough to accommodate the reciprocating motion of the iron E.

The link C is fastened to the arm B by the pin b, on which it oscillates. The crank g is a little off the center of the shaft F, so that 45 when the shaft is rotated it will cause the block D, through which the crank passes, to move forward and backward, this moving the link C and imparting a reciprocating or slightly oscillating motion to the iron E. 50

The top surface of the machine is made flat.

The machine is operated as follows: The upper or vamp, the edge of which has been blacked, is placed flatwise on the top of the machine, and the edge passed along in the 55 crease of the rapidly-reciprocating iron.

The machine is made small, so that it may be fastened to a bench and operated by a belt connecting it with the floor-shafting, in the same manner as an ordinary sewing-machine. 60

To obtain the best results, the iron E should be heated, which can be done by passing gas through a small tube till it comes in contact with the iron, or by means of a lamp, either of which methods is well known and needs no 65 particular description.

Having fully described my invention, what I claim, and desire to secure by Letters Patent, is—

A vamp-burnishing machine consisting, essentially, of a frame, A, provided with a table or plate, a burnishing-iron, E, projecting through a slot or aperture therein, and means, as link C, block D, and crank g, for imparting to said burnishing-iron an oscillating or 70 reciprocating motion, substantially as described. 75

WILLIAM F. HUTCHINSON.
